UNITED STATES PATENT OFFICE.

ART T. MILLS, OF WARSAW, MISSOURI.

FOLDING CAR-STEP.

1,056,041.

Specification of Letters Patent. Patented Mar. 18, 1913.

Application filed July 31, 1911. Serial No. 641,409.

To all whom it may concern:

Be it known that I, ART T. MILLS, a citizen of the United States, residing at Warsaw, in the county of Benton and State 5 of Missouri, have invented certain new and useful Improvements in Folding Car-Steps, of which the following is a specification.

My invention relates to improvements in folding car steps, and has for its object 10 the provision of an improved form of folding car step particularly adapted for use on railway trains.

The further object of my invention is the provision of an improved form of folding 15 car step which may be readily operated from the platform of the car and which may be readily attached to the ordinary permanent or stationary steps of the car and will serve to fill in the space between the lowermost 20 permanent step of the car and the ground to facilitate the mounting of the steps by the passengers or the dismounting from the train and obviate the necessity for a number of porters each provided with a foot 25 stool as is now generally necessary to assist passengers desiring to board or alight from the railway car.

Other objects and advantages of my improved folding car step will be readily apparent by reference to the following description taken in connection with the accompanying drawings, and it will be understood that I may make any modifications in the specific structure shown and described 35 within the scope of my claims without departing from or exceeding the spirit of my invention.

Figure 1 represents a fragmentary end view of a car equipped with my improved 40 folding step showing the step in folded position. Fig. 2 represents a similar view to Fig. 1 but illustrating the step in its lowered position ready for use. Fig. 3 represents a fragmentary side elevation of the car showing 45 the improved step in operative position, and Fig. 4 represents a sectional view of the device for locking the shifting lever and thus the step in adjusted position. Fig. 5 is a sectional view on line 5—5 of Fig. 4.

50 In the drawings, the numeral 1 designates the body of a car having the platform 2 provided with the guard rail 3 and having depending from the sides the supporting frame work 4 for the customary permanent car step 5. The said step 5 as is customary with railroad car steps is so constructed as to lie

entirely within the side lines of the car and as to be spaced a considerable distance above the ground and consequently said steps are difficult to mount unless the train is 60 stopped beside a raised platform. To enable persons to readily mount the said steps when the train is stopped but at the same time to allow the steps to be ordinarily within the side lines of the car and spaced above the 65 ground and to prevent persons from jumping onto the steps when the train is in motion, I have provided my improved form of folding car steps.

Pivotedly secured to the lowermost permanent car step 5 by the hinges 6 is the uppermost riser 7 of the folding steps 8 which are sufficient in number to extend from the lowermost step 5 almost to the plane of the rails to allow of ready mounting of the 75 steps when the folding steps are lowered. To control the movement of the said folding steps and to raise or lower the same as desired, I secure to the lowermost step 5 by the pivot 9 the controlling lever 10 which is 80 engaged intermediate its length on the pivot 9 and has formed in one end the slot 11 in which rides the lug or pin 12 secured to the steps 8, whereby by on rocking of the lever 10 on its pivot 9 to raise the slotted end 85 thereof the folding steps 8 will be swung upward on their hinges 6 and will rest against the main step 5 of the car, as is clearly shown in Fig. 1, the riding of the pin 12 in the slot 11 facilitating said movement 90 of the step by allowing of relative movement of the step with respect to the end of the lever which is necessary on account of the difference in the point of pivotance 95 of the lever and of the step. To regulate the said rocking of the lever 10 and to enable one of the trainmen to operate the step without dismounting from the car 1, I pivotally secure to the opposite end of the lever 10 from that having the slot 11 100 the controlling rod 13 having a handle 14 at its upper end, said lever 13 having its upper portion 15 provided with locking notches 16 formed therein, the upper portion 15 of said lever passing between the arms 105 of the yoke 17, said yoke being secured to the block 18 of the railing 3 of the car. Said block 18 has a beveled portion 19 adapted to be engaged in one of the notches 16, of the rod 13 to lock the rod and thus the steps in 110 adjusted position.

To cause the automatic locking of the said

rod 13 in adjusted position, I slidably engage on the arms of the yoke 17 the plate 20 having extending centrally therefrom the pin 21 slidably engaged in a passage formed 5 in the arch of the yoke while wound upon the said pin 21 is the helical spring 22 bearing at one end against the yoke and at the other end against the plate 20 to force said plate inwardly. Said plate 20 rests against 10 the upper portion 15 of the rod 13 and serves to automatically press the said rod inwardly to force one of the notches against the beveled portion 19 of the block 18 and thus lock the controlling rod 13. When it is desired to 15 shift the step it is merely necessary to press the handle 14 outward to disengage the portion 15 from the block 18 and then to shove or draw on the rod 13 according to whether the step is to be raised or lowered.

20 From the foregoing description taken in connection with the accompanying drawings, the construction and operation of my improved car step will be readily understood, and it will be seen that I have provided 25 a thoroughly simple and efficient form of folding car step which may be readily attached to any ordinary railway car and which will prove efficient in that when lowered the folding step will facilitate mounting or alighting from the car, while when in 30 raised position the riser 7 of the folding step will rise above the lowermost permanent step 5 of the car and will consequently provide a considerable obstacle to a person desiring to mount the steps when the train is 35 in motion, and will consequently serve to deter persons from attempting to mount the steps and will consequently prevent accidents which often occur through persons endeavoring to mount the steps of a car while 40 the same is in motion.

I claim:

1. The combination with the permanent steps of a car, of supplemental steps having 45 their uppermost riser pivoted to the lowermost permanent step, a lever intermediately

pivoted to the lowermost permanent step and having a slot formed in one end, a pin projecting from one of the folding steps and riding in the slot in the lever, whereby rocking 50 of the lever serves to shift the lever to, control the position of the folding step.

2. The combination with the permanent steps of a car, of supplemental steps pivoted thereto, a lever intermediately pivoted to 55 one of the permanent steps and having one end connected to the folding steps, whereby rocking of the lever serves to swing the folding steps to lie on top of the permanent steps or to swing the same downward into operative position.

3. The combination with a car having permanent steps, of folding steps pivoted to the lowermost permanent step, a lever intermediately pivoted to said lowermost permanent step and having a slot formed in one end, a pin projecting from the folding steps and riding in the slot in the lever, an operating rod pivoted to the other end of the lever, and means for automatically locking 70 the rod in adjusted position to prevent accidental movement of the steps.

4. The combination with the permanent steps of a car, of folding steps pivoted thereto, an operating lever pivoted to the lower- 75 most permanent step, connections between the operating lever and the folding steps for swinging the latter on their pivots, a controlling rod pivoted to the operating lever, a guide yoke for said rod, a block carried by 80 the car to which the guide yoke is secured, said block being provided with a beveled portion and a spring device for pressing the controlling rod into locking engagement with the beveled portion of the block. 85

In testimony whereof I affix my signature, in the presence of two witnesses.

ART T. MILLS.
